DESIGN FOR A ROAD SIGN

Idell Tyler and Mitchell Malyszek,
Marquette, Mich.

Application June 25, 1940, Serial No. 93,242

Term of patent 3½ years

To all whom it may concern:

Be it known we, Idell Tyler and Mitchell Malyszek, citizens of the United States, residing at Marquette, in the county of Marquette and State of Michigan, have invented a new, original, and ornamental Design for a Road Sign, of which the following is a specification, reference being had to the accompanying drawing, forming a part thereof.

The figure is a plan view of a road sign, showing our new design.

The article is of no appreciable or substantial thickness.

We claim:

The ornamental design for a road sign, as shown and described.

IDEELL TYLER.
MITCHELL MALYSZEK.
